DESIGN FOR WALL-PAPER.

Design No. 12,517, dated October 11, 1881.

UNITED STATES PATENT OFFICE.

EDUARD LEISSNÈR, OF NEW YORK, N. Y., ASSIGNOR TO LEISSNÈR & LOUIS,
OF SAME PLACE.

DESIGN FOR WALL-PAPER.

SPECIFICATION forming part of Design No. 12,517, dated October 11, 1881.

Application filed August 25, 1881. Term of patent 3½ years.

To all whom it may concern:

Be it known that I, EDUARD LEISSNÈR, of New York, in the county and State of New York, have invented a new and original Design for Wall-Paper, of which the following is a specification.

This invention relates to a new and original design for wall-paper and similar fabrics; and it consists in the novel grouping and configuration of parts hereinafter more fully described.

The accompanying photograph illustrates a face view of a wall-paper having my new design.

15 The upper border, *a*, is composed of double upright arches, each double arch having a floral ornament in its lower portion. The lower border, *b*, is formed of two serpentine stripes containing small rosettes in the circles that result 20 from the windings of said stripes. The border *b* has beaded top and bottom edgings. Between these two borders *a* and *b* is a vine formed into two large scrolls, *A* and *B*. The scroll *A* contains within its center a conven-

tional flower, *c*, with long projecting pistil, the 25 end of which encircles the body of the vine. The scroll *B* contains a central group, *d*, of flowers, below which there are leaves. Partly-contracted leaves *f* embrace the stem that forms the vines *A* and *B*. Below the vine *A* 30 is also a fruit-like projection resting on the border *b*.

I claim—

1. The design for wall-paper, consisting of the border *a*, substantially as shown. 35
2. The design for wall-paper, consisting of the border *b*, substantially as shown.
3. The design for wall-paper, consisting of the scrolls *A* *B*, having ornaments *c* *d* *e* *f*, substantially as shown. 40
4. The design for wall-paper, consisting of scrolls *A* *B*, having ornaments *c* *d* *e* *f*, and of the borders *a* and *b*, substantially as shown.
